UNITED STATES PATENT OFFICE.

OWEN ALFRED PRICE, OF KILMARNOCK, SCOTLAND.

HYDRAULIC JET-DISPERSAL NOZZLE.

Application filed August 28, 1923. Serial No. 659,807.

To all whom it may concern:

Be it known that I, OWEN ALFRED PRICE, a British subject, and a resident of Kilmarnock, Scotland, have invented certain new and useful Improved Hydraulic Jet-Dispersion Nozzles, of which the following is the specification.

This invention has for its object to provide means for dispersing and cushioning the destructive energy in high velocity streams of water, and which for instance exists at the outfall of undersluices or discharge regulators for high dams, or in similar cases where high level water is freely discharged into comparatively shallow river beds, watercourses, reservoirs, penstock chambers, conduit basins, ponds and the like.

It has hitherto been the practice to allow such streams or jets to strike the downstream water as solid masses possessing concentrated energy which is expended as local shock. Consequently very great damage has been done to the water bed and, due to the swirling currents set up, injury has been done to the masonry and foundations at the foot of the dam and to the banks and surrounding structures. In the great majority of cases where large high velocity streams are ejected the provision of a water cushion of sufficient depth and width to be effectual is a prohibitive undertaking on account of the great cost of the works. As an alternative, or, in addition to some form of water cushion, it is customary to dump large boulders, blocks of masonry and concrete into the water bed and to renew these as they become eroded away or become sunk into the water bed by the eddying and swirling action of the water on the finer material composing the bed.

According to the invention means are provided immediately adjacent to the nozzle discharge outlet for the creation of one or more free spiral vortices in the stream immediately before its release to the atmosphere the means being such that the device may be predeterminedly adapted to the water pressure, its volume and the space available for dispersion. Thus the stream is discharged as one or more conical showers of drops which are cushioned entirely against the atmosphere and scattered as heavy rain drops over a very wide area many hundred times as great as the shock area of the same stream when solid. Whatever velocity and

energy is possessed by the solid issuing stream, the dispersed water cannot meet the downstream water at a velocity greater than that of ordinary heavy falling rain, the damaging effect of which, under the circumstances, is altogether negligible. Local destruction and swirling currents, also are impossible as the delivered water falls in a sheet of drops possessing no penetrating power, and induces a gentle uniform current over the whole width of the downstream bed.

Diffusing nozzles have been proposed in which an inflowing stream is divided into several streams of differently directed motions so as to cause mutual interference and ultimate mixing accompanied by a condition of turbulence.

Also, in spraying nozzles it has been proposed to produce a flaring discharge by imparting a tangential velocity to the escaping stream, this tangential velocity being produced either by the impact of tangential jets or by helically or spirally disposed vanes, the result in either case being to produce a distribution of rotary velocity such that the tangential velocity is directly proportional to the radius, that is to say, the angular velocity is constant in any plane at right angles to the axis. Similar devices which produce identically the same conditions of velocity distribution in the stream have also been proposed in connection with Pelton wheel governing, and for dispersing pressure water escaping from relief valves on water turbine supply pipes when the stream is diverted into confined spaces. But in these cases the jets have been generally small in size, and under considerable pressure, thus resulting in very high velocities. The condition at the outlet orifice has been that of a suddenly released forced vortex, and under these conditions the jets have been effectually broken up, while the back pressure absorbed in the process has been of no consequence. At the same time the ideal conditions necessary for the most economical and most perfect dispersion of the stream have not been obtained. In application of the present invention, the jets will usually be several feet in diameter and the available heads relatively low. Also on account of the totally different objects in view, a perfectly uniform and complete dispersion is required with the consumption of the least possible energy head.

Theoretical considerations suggest, and experiments have demonstrated that if a free-spiral-vortex is allowed to escape freely into the atmosphere the various co-axial free spiral currents of which it is composed cease rotating and pursue a straight line course. The free vortex condition hereinbefore referred to exists in a fluid flowing axially in a confined space of substantially cylindrical form if it has, combined with the axial component of flow, a tangential component so distributed, across a plane at right angles to the axis, that the said tangential component varies inversely as the radial distance from the axis. By virtue of the free vortex condition each concentric series of currents possesses a different absolute velocity which is inversely proportional to the distance from the axis, and consequently, each concentric series of currents pursues a different straight line course, those currents nearer the axis, because of their greater velocity, taking a more divergent course, relative to the axis, than those remote from the axis. The result is that the inner currents tend to pass through the outer currents, the released free-vortex becomes a hollow expanding cone of interlacing filaments to fluid and is rapidly shattered into drops. In this state it is susceptible to the air cushioning which is one of the principal objects of the invention.

In carrying out the present invention a nozzle is formed with one or more chambers 35 behind the orifice suitable in shape for the accommodation of a free-spiral-vortex and anterior to this space apparatus is provided to produce a forced-vortex of such a type that it most efficiently initiates that free 40 vortex possessing the desired predetermined properties. Various constructions may be adopted according to the size and velocity of the water jet and according as the nozzle is an independent fitting or is combined with 45 a stream-lined valve or other apparatus.

One form of independent nozzle, designed to throw a single hollow cone is preferably constructed of three parts. (1) A divergent conical portion intended to gradually enlarge the area of the stream in order to provide space for the insertion of the blading without constricting the free channel. (2) A blade element consisting of radiating vanes with or without a central boss which 50 may have a central passage through it from which the vanes radiate. The vanes are shaped so that they have but a small angle to the normal direction of flow (that is they are at a lesser angle to the axial plane than to the plane of rotation). Their pitch or angular disposition, relative to the axis of the nozzle, gradually becomes less as the distance from the axis increases, thereby imparting a greater tangential velocity to the 55 central water than to the water nearer the

circumference, thus setting up the forced-vortex conditions hereinbefore referred to. It is to be understood however that the rate of change of pitch of the vanes along the radius may be varied. And (3) a part 70 usually convergent and truncated, conical, conoidal, or dome-like providing the space for the consolidation of the natural free vortex and containing a circular outlet orifice in axial line. 75

In another form intended for a larger stream of water the general design is identical except that an inner conoidal shell is introduced dividing the free vortex chamber and the outlet orifice into two parts comprising a central core and an outer annular chamber. This conoidal shell is extended outwards beyond the main orifice. Such a nozzle throws two co-axial discharge cones, and according to the design of the blading 80 these cones may have equal or different angles of divergence. For a moderate sized stream the angles of divergence may be approximately equal, or the outer cone may be slightly more divergent than the inner cone. For a very large stream, however, the inner cone might have a wider angle of divergence than the outer cone so that the inner water would strike the outer water and shiver it more quickly than would be the case if disruption were left entirely to the disintegrating filaments within the hollow cone. 85

The advantage of throwing more than one cone becomes more valuable as the size of the stream increases, because, with a large jet the discharge cone would have to expand to a very large diameter indeed before it became sufficiently attenuated to become entirely broken into drops. The thickness of the hollow cone at which the water is completely shattered into drops is approximately constant for all sizes of jets and therefore a large stream if dispersed as a single cone, would expand to inconvenient dimensions before this completely shattered thickness was attained. For this reason multiple cones are used as described. 100

Multiple cones may also be produced by simply dividing the orifice by concentric tubular extensions into two or more bodies of water. In this case the inner cones are more divergent than the outer ones because they are supplied with water by the more rapidly rotating portion of the natural free 105 vortex, while the outer cone is supplied by the more slowly moving annulus. 110

When the dispersion nozzle constructed in accordance with the present invention is combined with a stream-lined valve as already referred to, the conoidal central boss from which the blades radiate and as already described, becomes modified to such proportions as will embrace the operating member of the valve. 115

Various other constructions may be adopted in accordance with the present invention, the essence of the contrivance being the combination in a nozzle of two types of vortex, 5 a forced vortex produced by blading of such form that the water leaving it rapidly consolidates itself into a free-vortex of predetermined properties, according to the water pressure available, the volume to be 10 discharged and the dispersion space available, this free vortex being formed within a suitably shaped chamber behind the nozzle orifice so that a perfectly stable free-spiral-vortex is released at the orifice. The 15 integration of this vortex when freely ejected allows of the great resistance of the air to act with cushioning effect upon the enormously increased superficial area produced by the perfect shattering of the stream into 20 uniformly small globules. The whole of the destructive energy is thereby dissipated and no harmful effect can occur at the surface upon which the water falls.

In another application of the invention, 25 the escaping streams are broken into drops in order to aerate the water for the purpose of improving its quality for town supply purposes and other uses.

Two sheets of explanatory drawings are 30 hereunto appended in which Figures 1 to 8, sheet 1, are sectional elevations showing somewhat diagrammatically eight examples of the improved nozzle. Figure 9 is a similar view showing the nozzle combined with 35 a stream-lined valve. The details of the specific construction shown in Fig. 9 are not claimed in this application as they form the subject of my divisional application, Ser. No. 719,203 filed June 10, 1924. Figure 40 10, sheet 2, is a sectional diagram indicating the course of the free spiral currents formed by free-vortex action whilst Figures 11 and 12 are like views showing how these currents cause a divergent conical formation 45 of the stream.

According to the example shown in Figure 1 the nozzle is designed to throw a single hollow cone of fluid and is constructed of three parts. (1) An inlet branch A of divergent conoidal formation intended to gradually enlarge the area of the stream. (2) A blade element composed of vanes B radiating from a central conoidal or stream-lined boss C. These vanes are shaped so that their 50 pitch or angular disposition relative to the axis of the nozzle gradually becomes less as the distance from the axis increases thereby imparting a greater tangential velocity to the central water than to the water nearer the circumference. The pitch of the vanes will vary according to the proportion of the work which it is desired that the vanes should accomplish, and the change of pitch of each vane in a radial direction will vary 55 according to the nature of the fluid being

treated and according to the surface resistance offered by the particular modification of device adopted, and (3) a convergent truncated conoidal part D having a circular outlet orifice in axial line. 70

This construction of nozzle therefore produces a forced-vortex, of such form that the water rapidly consolidates itself into a free-vortex within the chamber D and before its release to the atmosphere. 75

The construction shown in Figure 2 differs from that hereinbefore described in that the divergent conical inlet branch A₂ is shortened and made in a piece with the convergent outlet branch D₂. The diameter and 80 length of the central boss C₂ is also increased and the pitch of the vanes B₂ altered to suit the changed velocity of the fluid produced by the relatively restricted passage between the boss and the outer wall. The 85 full lines in this figure show the form of nozzle preferred when used with high pressure fluid and the dotted lines the preferred form for lower pressures.

The design shown in Figure 3 is intended 90 for use in connection with a comparatively large stream of water. In general outline it is similar to the example first hereinbefore described except that the part forming the "free-vortex" chamber is of more curved 95 form; that is, it diverges outward from the vanes B₃ and is convergent towards the outlet orifice; and an inner conoidal shell E₃ is introduced dividing the forced and free vortex chambers and the outlet orifice 100 into two parts comprising a central double conoidal chamber and an outer annular chamber D₃. This conoidal shell E₃ is extended outwards beyond the main outlet orifice. Such a nozzle throws two coaxial 105 discharge cones and according to the design of the blading B₃ these cones may have equal or different angles of divergence.

The example shown in Figure 4 shows the 110 application of this inner conoidal shell E₄ to a construction very similar to that shown in Figure 2.

Figure 5 differs from the example last hereinbefore described mainly in that the inner conoidal shell E₅ occupies only the 115 forward portion of the free-vortex chamber D₅.

In Figure 6 there is shown a construction which differs from that hereinbefore described practically only in that the central 120 boss C₆ is of hollow ring form. It has been found that this ring formation offers less surface friction to the water and eliminates all tendency to cavitation. The centre jet of water passing through the ring is revolved by the large body of water around it, and as no resistance to rotation exists, the centre revolves more quickly than otherwise, and so results in a quicker disintegration. The ring itself is employed for 125 130

constructional purposes only to hold the ends of the vanes rigidly in position. In small nozzles where the vanes are short and stiff the ring may be dispensed with and the vanes simply cut off leaving a clear central space. This ring construction may be embodied in any of the multiple cone examples shown in Figures 3, 4 and 5 with the same advantageous effects.

10 The example shown in Figure 7 differs from that last hereinbefore described in that, as shown in full lines, the free vortex chamber D_7 is of divergent form, and the dotted lines show that it may even be entirely cylindrical.

15 In Figure 8 is shown an example in which the divergent inlet A_8 and the convergent discharge D_8 are purely conical instead of curvilinear or conoidal as in the examples described with reference to Figures 1 to 6.

20 Figure 9 shows the application of the invention as combined with a stream lined valve of known form, the conoidal central boss C_9 from which the blades B_9 radiate, as hereinbefore described, being modified to such proportions as to embrace the operating member H of the valve which, in this example, closes in an upstream direction but may equally well be designed to close in a downstream direction. The free vortex chamber is the predetermining influence over the behaviour of the apparatus. The forced vortex chamber blades B_9 have angularly disposed faces imparting the necessary tangential velocities to the stream.

25 In Figure 10 it will be seen that the free-spiral vortex shown as escaping freely into the atmosphere comprises various coaxial free spiral currents which have ceased rotating and pursue a straight line course. By virtue of the free vortex condition, each concentric series of currents possesses a different absolute velocity which is inversely proportional to the distance from the axis, and consequently each concentric series of currents pursues a different straight line course, those currents J nearer the axis, because of their greater velocity, taking a more divergent course, relative to the axis, than those K remote from the axis. The result is that the inner currents J tend to pass through the outer currents K , the released free-vortex becomes a hollow expanding cone of interlacing filaments of fluid and is rapidly shattered into drops.

30 Figure 11 shows how the jet becomes thinned before disruption. These two Figures 10 and 11 show the jet thrown by the examples hereinbefore described with reference to Figures 1, 2, 6, 7, 8 and 9.

35 Figure 12 shows the two coaxial discharge cones of water thrown from the examples of nozzle described with reference to Figures 3, 4 and 5. Of course it is to be understood that the angles of divergence

of these cones depend upon the pitch of the blading, the inner cone having, as shown, a greater angle of divergence than the outer cone so that the inner water strikes the outer water and shivers it more quickly than would be the case if disruption were left entirely to disintegration with the hollow cone.

40 What I claim is:—

1. A jet-dispersal nozzle comprising in combination and coaxially arranged an inlet portion, a blade element consisting of radiating blades each of a pitch that decreases progressively from the central portion of the stream toward the periphery, and adapted to form a forced spiral vortex that will rapidly consolidate to a free spiral vortex, and all coacting in such manner that the central portion of the stream is revolved with a higher velocity than the peripheral portion, as and for the purposes set forth.

45 2. A jet-dispersal nozzle comprising in combination and coaxially an inlet portion, a blade element consisting of radiating blades whose pitch varies inversely with the radius and adapted to form a forced vortex that will rapidly consolidate to a free spiral vortex, and an outlet portion adapted to accommodate a free spiral vortex, and all coacting in such manner that the central portion of the stream is revolved with a higher velocity than the peripheral portion, as and for the purposes set forth.

50 3. A jet-dispersal nozzle comprising in combination and coaxially a divergent inlet portion, a blade element consisting of radiating blades whose pitch varies inversely with the radius, a central boss and an outlet portion, as and for the purposes set forth.

55 4. A jet-dispersal nozzle having in combination and coaxially a blade element having means adapted to impart a greater tangential velocity to the central liquid than to the liquid nearer the circumference, and an outlet portion adapted to form a free spiral vortex.

60 5. A jet-dispersal nozzle having in combination and coaxially a blade element including vanes whose angular disposition relative to the axis of the nozzle gradually becomes less as the distance from the axis increases, and an outlet portion adapted to form a free spiral vortex from the liquid received from the blade element and containing a circular orifice for the jet.

65 6. A jet-dispersal nozzle comprising, in combination, and coaxially arranged, an inlet portion, a blade-element consisting of radiating blades whose pitch varies inversely with the radius, a central boss having an axial aperture, and an outlet portion.

7. A jet-dispersal nozzle comprising, in combination, and coaxially arranged, an inlet portion, a blade element consisting of

radiating blades, whose pitch varies inversely with the radius, adapted to form a forced spiral vortex that will rapidly consolidate to a free spiral vortex, an outlet portion to accommodate the free spiral vortex, and a central boss from which the blades radiate.

8. A jet-dispersal nozzle, comprising, in combination, and coaxially arranged, an inlet portion, a blade element consisting of ra-

dinating blades, whose pitch varies inversely with the radius, adapted to form a forced spiral vortex that will rapidly consolidate to a free spiral vortex, an outlet portion to accommodate the free spiral vortex, and an 15 axially apertured member within said nozzle.

In testimony whereof I have signed my name to this specification.

OWEN ALFRED PRICE.
